COMBINED STAPLE AND STRAP

Charles C. Wickwire, Cortland, N. Y., assignor to
Wickwire Brothers, Cortland, N. Y., a corporation of New York

Application April 5, 1934, Serial No. 719,228

1 Claim. (Cl. 85—49)

This invention relates to staples, and particularly to a combined staple and strap adapted to hold insulated cables of the type having a soft and easily broken covering of insulation.

In the prior art, various types of staples have been used for the purpose of fastening and anchoring cable, and for holding insulated wire. The fastening of armored cable offers no particular problem, since the armor is capable of withstanding considerable compressive strength without possibility of injuring the insulation. Where insulated staples, that is, metal staples having straps or clips of insulation, are used for holding insulated wiring having a soft covering, the strap or clip acts as a buffer and as a protective means, so that the insulation on the wire is not injured if the staple is driven in too deep.

Where metal staples are used for securing large cables without armor covering, a different problem arises. Not only is the insulation soft and readily injured by too much compression, but the fire underwriters' requirements make it necessary to provide means for guarding against such injury. These requirements necessitate the use of a staple having a substantially flat top and a strap or clip which is likewise broad, flat, and smooth, so that, when the staple is driven into a joist or other support sufficiently to clamp the cable, there will be no rupturing of the insulation.

For the most part, this latter structure has been of a two-piece construction, wherein a flat metal clip or strap is perforated at two points to receive the legs of the staple. Such an arrangement is clumsy and impractical because it requires assembly of the two parts and this consumes much time and is awkward when installations are to be made in constricted locations and in locations difficult of access.

Accordingly, the main object of this invention is to produce a one-piece staple having a flat wide clip or strap integrally secured to the staple and capable of holding a soft covered cable in position without rupturing the insulation.

The invention will be best understood when the following specification is read in conjunction with the accompanying drawing, in which:

Fig. 1 is a perspective view of one form of staple embodying this invention; and

Fig. 2 is a similar view of a modification.

Referring to Fig. 1, the reference character 3 designates a one-piece metal staple composed preferably of steel wire and having a body or head 4 and two sharpened legs 5 depending substantially at right angles to the body. Mounted between the legs 5 underneath the body 4 and se-

cured thereto at 6 is a flat metal strap or clip 7, having a longitudinal extent substantially in excess of the width of the body. This strap or clip 7 is electrically welded to the body 4, since electric welding can be carried out simply, cheaply, and expeditiously, and forms the staple and clip into a single integral structure. The bottom face of the clip is smooth, flat and broad and can be driven into firm engagement with the cable insulation to lock the cable in position without any possibility of injuring the insulation, and without any assembly operation prior to use.

It will be understood that the staple 3 is handled in the usual manner, the legs being placed astride the cable to be anchored. The points are driven into the joist or other support where the cable is to be mounted until the strap or clip 7 comes into tight engagement with the insulation of the cable and sufficiently to anchor the cable firmly in position. The staple can be placed in position without any previous assembly operation, since it comprises a single, one-piece structure to be handled, and all possibility of injuring the cable is positively avoided, because the flat clip 7 has no sharp projecting edges which can bite into the insulation. This affords a distinct advantage over devices of the prior art wherein means were provided for limiting the depth to which the staple can be driven. In those cases it was necessary to have the limiting means properly positioned in accordance with the dimensions of cable to be anchored, and it was difficult to get the proper frictional contact between the staple and the cable. The device of this invention avoids in a simple manner all the difficulties of the prior art and provides a simple, integral construction which not only can be made cheaply, but it meets the underwriters' requirements in every particular.

Under some conditions, it may be desired to extend the strap or clip laterally to form flanges depending inside the legs 5. Such a structure is shown in Fig. 2 of the drawing, wherein the parts are designated by the same reference characters as those just indicated, except that the strap is here designated 8 and has, in addition to the substantially flat central portion underneath the body 4, depending curved portions or flanges 9 which may embrace the sides of the cable to further support it and guide it, and to provide an additional means for preventing possible rupture of the cable insulation when the staple is driven into position.

Although various types of staples have been suggested for this use in the prior art, no one has provided a simple construction of staple and clip

wherein the two parts are electrically welded together in fixed and permanent relation so as to avoid the inconvenience of assembling the parts when the staples are to be used.

5 While only two forms of staple embodying this invention have been shown and described, it will be obvious that changes may be made in the details within the scope of the appended claim without departing from the spirit and scope of the invention.

10 What is claimed is:—

A unitary staple for clamping cables having a soft covering of insulation, comprising a substan-

tially straight metal body of steel wire having two spaced legs depending substantially at right angles to said body; and a broad flat metal clip substantially bridging the space between said legs and projecting materially beyond said body on both sides thereof longitudinally of the cable to be held and electrically welded to the under side of said body between said legs and presenting a smooth flat surface adapted to engage and compress the insulation on said cable over an extended area when said legs are driven into a supporting surface. 5 10
